DESIGN FOR A TEXTILE FABRIC

Furth Ullman, New York, N. Y., assignor to Joseph Berlinger Co., New York, N. Y., a corporation of New York

Application May 31, 1940, Serial No. 92,702

Term of patent 3½ years

To all whom it may concern:

Be it known that I, Furth Ullman, a citizen of the United States, residing in the city of New York, in the county of New York, and State of New York, have invented a new, original, and ornamental Design for a Textile Fabric, of which the following is a specification, reference being had to the accompanying drawing, forming part thereof.

The figure is a plan view of a textile fabric,
showing my new design.

I claim:

The ornamental design for a textile fabric,
substantially as shown.
